UNITED STATES PATENT OFFICE.

THURE LARSSON, OF WORCESTER, MASSACHUSETTS, ASSIGNOR TO HIMSELF, WILLIAM E. D. STOKES, OF NEW YORK, N. Y., AND FRED A. JONES, OF WORCESTER, MASSACHUSETTS.

AUTOMATIC STOPPING MECHANISM FOR ELEVATORS.

1,033,181.

Specification of Letters Patent. Patented July 23, 1912.

Application filed April 3, 1905, Serial No. 253,573. Renewed May 27, 1912. Serial No. 700,082.

To all whom it may concern:

Be it known that I, THURE LARSSON, a subject of the King of Sweden, residing at Worcester, in the county of Worcester and 5 State of Massachusetts, have invented a new and useful Automatic Stopping Mechanism for Elevators, of which the following is a specification.

This invention relates to a governor-device inside the plunger casing of a plunger elevator for controlling the outlet to the to-and-from pipe in case of accident; and to a combination of the governor device with a stop mechanism.

15 In the accompanying three sheets of drawings, Figure 1 is a side view partly broken away of sufficient parts of a plunger elevator to illustrate the application of this invention thereto. Fig. 2 is a plan view of 20 the same. Fig. 3 is a diagrammatic view illustrating the action of the governor device inside the plunger casing. Fig. 4 is a sectional view of the casing-head. Fig. 5 is a transverse sectional view thereof. Fig. 6 25 is a fragmentary view of the governor device. Fig. 7 is a side view of sufficient parts of a plunger elevator plant to illustrate a modified form of construction and, Fig. 8 is a sectional view of the stop-valve which 30 cuts off the exhaust from the to-and-from pipe when the car reaches the bottom of its run.

The principal object of my invention is to provide an automatic governor device for 35 controlling a hydraulic plunger elevator in case of accident, and to combine the governor device with an automatic stop mechanism.

The governor device is preferably located 40 inside the cylinder-head, and as herein illustrated, this governor device consists of a shell having a port normally registering with the opening of the to-and-from pipe. In case of unusual or an abnormal decrease 45 of the operating pressure in the cylinder casing, the governor device will rise or be shifted so as to throttle or entirely cut off connection with the to-and-from pipe, thus slowing down the speed of the elevator.

50 The governor device may be brought into operation by accidents, such, for example as the breaking of the to-and-from pipe; while the combined action of the governor mechanism and stop devices provides a variable

stopping action which will vary in accordance with the speed at which the car is descending. That is to say, while the ordinary stopping connections are intended to commence the operation of retarding the car and finally bringing the car to rest at fixed points; by combining a governor mechanism with my stopping devices I am able to secure a variable stopping effect which will have an earlier retarding action in accordance with the speed at which the car is descending.

Referring to the drawings and in detail for a description of construction embodying this invention, C designates the plunger casing of an ordinary elevator. Running up 70 and down in the casing C is a plunger P which carries at its upper end the car D. The car D as shown in Fig. 2 is guided on suitable ways, and also guided in ways at the side of the car D is a counterweight W. 75 The stopping devices may be operated either from a suitable abutment or wheel on the car, or from the counterweight.

The water supplying connections for the plunger casing may be arranged as shown in 80 Fig. 7, and comprises the to-and-from pipe T which may be connected through a stop-valve 12 and the main valve V to the outlet 11, or which may be connected through a stop-valve 13 and the main valve V to the 85 inlet 10. The stop valves 12 and 13 are of similar construction, and the outlet stop valve 12 is illustrated in Fig. 8.

In order to provide a contact bar which will operate reliably to stop a high speed 90 elevator it is essential that the bar should be stiff enough to resist the heavy strains due to the impact with the moving car or counterweight, and in order to provide a stiff and reliable construction, I provide an arrangement of connected linkwork which forms, in effect a truss.

As shown in Fig. 1, 14 designates the contact bar which is engaged by a roller or abutment A on the car. The contact bar 100 14 is supported near its upper end by a bell-crank 15, near its center by a bell-crank 16 which is connected thereto by an adjustable link 17, and near its bottom by a bell-crank 18 which is connected thereto by an adjustable link 19. The other arms of the bell-crank 16 and 17 and the sector 18 are connected by a tension member or rod 20.

By means of this construction it will be seen that the contact bar 14 is supported at a plurality of points, and that any tendency to bend or deflect the contact bar 14 will be resisted by the strength of the tension member or rod 20. In some cases, as shown for example in Fig. 7, two sets of link-work may be employed, one at the top of the run and the other at the bottom of the run, both sets of link-work being operated by the elevator car, and the bottom set of link-work being connected by suitable connections to operate the stop valve 12; while the link-work at the top of the run may be connected 10 to operate the stop-valve 13. Each of the stop-valves 12 and 13 is intended to automatically stop the flow of water through the to-and-from pipe. For example, the stop-valve 12, as shown in Fig. 8, is provided 15 with a piston Z which shuts off connections with the outlet pipe 11 and stops the car when it reaches the bottom of its run. The stop-valve 13 for automatically stopping that car at the top of its run is of similar 20 construction and need not be illustrated nor described at length. In some cases, however, instead of employing link-work at the top and bottom of the run, all the stopping connections may be arranged at the bottom of 25 the run, one set of link-work for stopping the car as it is coming down being controlled by the car itself, and the second set of connections for stopping the car at the top of its run being controlled by an abutment or 30 wheel B carried by the counterweight W, the counterweight being set to reach the bottom of its run at the same time that the car reaches the top of its run.

The construction of the governor device 40 is most clearly illustrated in Figs. 4 to 6. As shown in these figures, the plunger casing C is provided with an opening 28 for the to-and-from pipe T, and mounted inside the plunger casing is a shell 29, having a 45 port normally registering with the opening 28. Opening above the governor device or shell 29 is a throttling passage 31 having a throttling screw 32. The passage 31 normally equalizes the pressure above and below 50 the governor device, but in case of an abnormal fall of pressure to the piston casing, such for example as would be caused by the breaking of the to-and-from pipe, the governor device or shell 29 would be raised 55 from its seat, thus throttling or entirely cutting off connection with the to-and-from pipe, and either retarding or stopping the fall of the elevator car. This automatic governor device inside the casing of a plunger elevator I combine to advantage with the 60 stop devices for stopping the car at the bottom of its run.

As shown in Fig. 1, the sector 18 has gear-teeth meshing with a pinion on a horizontal 65 shaft 24. Connected with the horizontal

shaft 24 by bevel gears is a second horizontal shaft 25 which extends into a casing 26 on the side of the plunger head.

As shown in Figs. 4 and 5, the shaft 25 is provided with a worm-wheel 27 which meshes with inclined teeth or grooves 30 in the governor device 29. By means of this construction when the governor device 29 is automatically lifted or raised, its upward travel will be guided by the engagement of the worm with the grooves therein, so that it will be partly turned or rotated. This is of advantage, as it provides a variable throttling of the elevator in case of emergency. This is illustrated in Fig. 3, 80 which shows three possible positions of the port or opening of the governor device 29. That is to say, when the governor device is lifted it will not only have throttling action on account of its vertical motion, but it will 85 also be more or less turned, so that less motion will be required from the link-work to entirely close connection between the plunger casing and the to-and-from pipe than when the governor device is in its 90 lower or normal position, and it is due to this that by combining the governor device with the stop mechanism, I am enabled to get a differential stopping action, acting more promptly in case of emergency than 95 during ordinary service conditions.

I am aware that many changes may be made in practising my invention by those who are skilled in the art, and while my invention so far as it relates to the governor 100 device is particularly adapted to a hydraulic plunger elevator, it is to be understood that my stopping mechanisms are also applicable to elevators of other types. I do not wish, therefore, to be limited to the particular 105 constructions I have herein shown and described, but

What I do claim and desire to secure by Letters Patent of the United States is:—

1. In a plunger elevator system, the combination of a plunger casing, a plunger vertically movable therein, a to-and-from pipe connected to the plunger casing, a throttling device mounted in the plunger casing, and consisting of a shell having a port normally 110 registering with the opening to the to-and-from pipe, and a restricted passage admitting pressure above the shell, whereby the shell will be lifted by fluctuations of pressure to the plunger casing to throttle the 115 connection with the to-and-from pipe.

2. In a plunger elevator system, the combination of a plunger casing, a plunger vertically movable therein, a car on the upper end of the plunger, a to-and-from pipe connected with the plunger casing, a throttling device inside the plunger casing, and connections for actuating the throttling device as the car approaches the end of its run. 125

3. In a plunger elevator system, the com- 130

- bination of a plunger casing, a plunger vertically movable therein, a car on the upper end of the plunger, a to-and-from pipe connected with the plunger casing, a rotatable shell mounted inside the plunger casing and acting as a throttling device between the plunger casing and the to-and-from pipe, and connections for turning the shell when the car approaches the end of its run.
- 10 4. In a plunger elevator system, the combination of a plunger casing, a plunger vertically movable therein, a car on the upper end of the plunger, a to-and-from pipe connected with the plunger casing, a throttling device inside the plunger casing operated by fluctuations of pressure to the plunger casing, and connections for also operating the throttling device as the car approaches the end of its run.
- 15 5. In a plunger elevator system, the combination of a plunger casing, a plunger vertically movable therein, a car on the upper end of the plunger, a to-and-from pipe con-

nected with the plunger casing, a shell inside the plunger casing acting as a throttling device between the plunger-casing and the to-and-from pipe, and a worm-wheel connection for operating the shell when the car approaches the end of its run, said worm-wheel connection also serving to turn the shell when the same is lifted by fluctuations of pressure to the plunger casing, whereby a variable stopping action is secured.

20 6. In an elevator, the combination with a car and its plunger, of a cylinder having an enlarged portion, and means within said enlarged portion for regulating the speed of travel of the car.

In testimony whereof I have hereunto set my hand, in the presence of two subscribing witnesses.

TURE LARSSON.
